UNITED STATES PATENT OFFICE

EDWARD A. WRIGHT, OF WICHITA, KANSAS

DESIGN FOR A TOY AIRPLANE

Application filed February 21, 1930. Serial No. 34,613. Term of patent 14 years.

To all whom it may concern:

Be it known that I, EDWARD A. WRIGHT, a citizen of the United States of America, residing at Wichita, in the county of Sedgwick and State of Kansas, have invented a new, original, and ornamental Design for Toy Airplane, of which the following is the specification, reference being had to the accompanying drawings, forming a part thereof.

Figure 1 is a perspective view of a toy airplane showing my new design.

Figure 2 is a sectional view on the line 2—2 of Figure 1 and

Figure 3 is a sectional view on the line 3—3 of Figure 1.

I claim:

The ornamental design for a toy airplane as shown.

In testimony whereof I affix my signature.

EDWARD A. WRIGHT.
